UNITED STATES PATENT OFFICE.

NATHAN M. LOWER, OF SCHENECTADY, NEW YORK.

LOCOMOTIVE-TENDER.

1,223,594.

Specification of Letters Patent. Patented Apr. 24, 1917.

Application filed March 21, 1916. Serial No. 85,551.

To all whom it may concern:

Be it known that I, NATHAN M. LOWER, a citizen of the United States, and resident of Schenectady, county of Schenectady, and 5 State of New York, have invented certain new and useful Improvements in Locomotive-Tenders, of which the following is a specification, and which are illustrated in the accompanying drawings, forming a part 10 thereof.

The invention relates to locomotive tenders provided with means for advancing fuel to the shoveling platform; its object being 15 to provide simple and efficient means for performing this function.

The invention consists broadly in a tender provided with one or more endless conveyors on the floor of its fuel bin, with suitable driving means therefor; and it consists 20 further in various details of construction as hereinafter described.

One embodiment of the invention is shown in the accompanying drawings, in which—

Figure 1 is a detail plan view of a locomotive tender provided with the coal-advancing means, some parts being removed;

Fig. 2 is a detail longitudinal vertical section of the tender, partly in elevation;

Fig. 3 is a detail in perspective of the conveyor;

Fig. 4 is a sectional detail on the line 4—4 of Fig. 1;

Fig. 5 is a sectional detail on the line 5—5 of Fig. 2;

Fig. 6 is a longitudinal sectional view of the motor and its connections.

Fig. 7 is a sectional view of the ratchet mechanism interposed between the motor and conveyor; and

Fig. 8 is a detail of the same mechanism, partly in elevation and partly in section.

The tender as shown is provided with the usual water tank 10, and a fuel bin the shoveling platform of which is shown at 11. The slope sheet of the fuel bin is shown at 12, and the tender is provided with a deck 13 back of the slope sheet and above the tank, upon which a quantity of coal or fuel may be stored,—a bulkhead 14 constituting 50 the back wall of this carrying space.

One or more endless conveyors, generally designated by the numerals 15, 16, are located upon the bottom of the fuel bin of the tender, and extend from the rear end there- 55 of to the shoveling platform. In the embodiment of the invention shown these car-

riers are two in number and extend from the bulkhead 14 at the rear end of the deck downwardly over the slope sheet 12. Each carrier is made up of link sections, as 17, 18, 19, each section comprising a flat faced cross-bar 20 and a pair of side arms or link members 21, 22, each cross-bar being provided with perforated lugs 23 to which the side bars of the following section are pivotally attached. The conveyor turns over sheaves or sprocket wheels 24, 25, at each end, and runs within a trough 26 secured to the floor of the bin.

This trough comprises a pair of side walls 27, 28, secured to the floor 13 and the slope sheet 12 by means of angle brackets 29, and it is also provided with a dividing plate 30, over and under which the conveyor travels. The trough 26 is covered by a plurality of 75 removable U-shaped caps 31, which rest upon the side walls 27, 28, and are held against longitudinal movement by means of stop lugs 32, secured to the side walls of the trough.

A suitable driving shaft 33 is provided for actuating the carriers, and when a plurality of carriers are provided, as shown, preferably the intermediate section of the shaft is inclosed in a protecting sleeve 34. The shaft 85 33 carries the sprocket or driving wheels or sheaves 24, and is driven by a suitable motor. For this purpose there is shown a reciprocating steam engine 35, positioned vertically in the forward end of the fuel bin and at 90 one side thereof. A rack bar 36, attached to the piston rod of the motor, cooperates with a gear wheel 37 loose on the shaft 33, suitable ratchet and pawl mechanism being provided for connecting the gear wheel to the 95 shaft.

As shown, this mechanism comprises a ratchet wheel 38, keyed to the shaft and inclosed within the gear wheel 37, and several sets of pawls, as 39, 40, pivoted to the gear 100 wheel and cooperating with the ratchet wheel for driving it in either direction. The pawls of each pair are connected by means of a retractile spring 41, tending to draw them together, and between them is located 105 an oscillatable lifting plate 42, carried by a circular plate 43, oscillatably mounted in a plate 44 attached to one face of the gear wheel 37. The length of the plate 42 is such that when it is in its central position both 110 of the pawls 39, 40, are held out of engagement with the ratchet wheel 38. Movement

of the plate 43 in either direction with reference to the gear wheel 37 will permit one of the pawls to engage the ratchet wheel under the influence of the spring 41.

5 The plate 43 is controlled by means of a lever 45, pivoted, as shown at 46, to the gear wheel 37, and connected by means of a retractile spring 47, to a stud 48 set in the rim of the gear wheel, this spring urging 10 the free end of the lever toward the shaft 33. An annular cone-shaped cam 49, sleeved upon a reduced end 50 of the shaft 33, cooperates with an inclined face on the lever 45, tending to move the lever backwardly 15 against the resistance of the spring 47. An axially oscillatable controlling handle bar 51, pivoted in suitable brackets 52, 53, is provided with a lateral arm 54 bearing against the outer face of the cam 49. As 20 this cam is moved inwardly by the turning of the handle bar 51, it swings the lever 45 away from the shaft 33, carrying with it the plate 43,—the lever being provided with a stud 55, playing in a radial slot 56 in this 25 plate. Normally the advancing pawl 39 is in engagement with the ratchet 38. The operator may, by turning the handle bar 51, disengage this pawl from the ratchet and bring the pawl 40 into coöperation there- 30 with for the purpose of reversing the direction of travel of the conveyers, should there be any clogging of the latter.

The motor 35 is controlled by a suitable valve 57, conveniently located, and preferably a valve is provided which is self-closing and will open both ends of the motor cylinder to the exhaust. Such valve not being specifically claimed in this application is not illustrated in detail.

40 The forward end of the conveyer is without cover. When the fuel in the forward end of the bin has been transferred to the locomotive fire-box, the operator starts the motor 35 and the conveyer transfers the fuel 45 resting upon its forward end to the shoveling platform 11. As the supply of fuel becomes depleted, the operator removes as many of the cover plates 31 as may be necessary to permit fuel in the rearward portion of the bin to fall upon the conveyer, and he may, therefore, ultimately transfer 50 all of the fuel, including that which is carried on the deck 13, forwardly to the shovel plate. Preferably the forward end of the 55 conveyer is housed within a chamber 58, formed within the water tank, so that the fuel leaves the conveyer substantially on a level with the shoveling floor.

While a simple and preferred form of 60 construction is here shown, various changes may be made in the details without departing from its scope.

While the fuel bin is shown as having a

sloping wall, and the conveyer is mounted directly on the fuel supporting wall, these 65 features are not of the essence of the invention in its broader aspects.

I claim as my invention—

1. In a locomotive tender, in combination, a fuel bin having a sloping back wall and a 70 fuel carrying deck extending backwardly therefrom, an endless conveyer located on such wall and deck, and means for driving the conveyer.

2. In a locomotive tender having a fuel 75 bin, in combination, a trough located on the fuel-supporting wall of the bin, an endless conveyer running in the trough, and a partition in the trough between the two turns of the conveyer, and means for driv- 80 ing the conveyer.

3. In a locomotive tender having a fuel bin, in combination, a trough located on the fuel-supporting wall of the bin, an endless conveyer running in the trough and a partition in the trough between the two turns of the conveyer, a plurality of removable cover plates for the trough, and means for driv- 85 ing the conveyer.

4. In a locomotive tender, in combination, a fuel bin having a sloping back wall; an 90 endless conveyer located on such wall, means for driving the conveyer, and ratchet and pawl connection between the driving means and the conveyer. 95

5. In a locomotive tender, in combination, a fuel bin having a sloping back wall, an 100 endless conveyer located on such wall, means for driving the conveyer, ratchet and pawl connection between the driving means and the conveyer, and means for reversing the driving direction of such connection.

6. In a locomotive tender, in combination, a fuel bin having a sloping back wall, an 105 endless conveyer located on such wall, means for driving the conveyer, ratchet and pawl connection between the driving means and the conveyer, such connecting mechanism comprising a ratchet wheel fixed on the drive shaft of the conveyer, a pair of oppo- 110 sitely facing spring-advanced pawls carried by a motor-driven wheel for coöperating with the ratchet wheel, an oscillatable plate having a finger projecting between the pawls, a lever pivoted on the wheel and en- 115 gagging the plate, a cone cam sleeved on the shaft and bearing against the lever, and a handle bar for advancing the cam.

7. In a locomotive tender having a fuel bin, in combination, an endless conveyer lo- 120 cated over the fuel-supporting wall of the bin and comprising a plurality of U-shaped pivotally united sections, the cross member of each section having a flat fuel-engaging face.

NATHAN M. LOWER.
